UNITED STATES PATENT OFFICE.

HARRY O. BRAWNER, OF BALTIMORE, MARYLAND.

DESIGN FOR A BOTTLE-STOPPER.

SPECIFICATION forming part of Design No. 34,996, dated August 27, 1901.

Application filed August 1, 1901. Serial No. 70,556. Term of patent 14 years.

To all whom it may concern:

Be it known that I, HARRY O. BRAWNER, a citizen of the United States, residing at Baltimore, State of Maryland, have invented and produced a certain new and original Design for Bottle-Stoppers, of which the following is a specification.

My design for a bottle-stopper is fully illustrated in the accompanying drawings, in which—

Figure 1 is a perspective view thereof. Fig. 2 is a side elevation thereof, and Fig. 3 is a top plan view.

The essential feature of my design comprises a bottle-stopper shaped substantially as shown in the accompanying drawings, wherein it will be observed that the bottle-stopper is formed with a cylindrical nipple 1, surmounted by a laterally-projecting circular flange 2, having a flat under face 3 and a curved upper surface, the latter of which merges into a rounded bead 4. Projecting upwardly from the bead 4 is a slightly-tapered fluted body portion 5, having the general out-

line of a frustum of a cone, and surmounting the fluted body portion 5 is a spherical knob 7, merging at its bottom into a rounded bead 6, the latter being interposed between the spherical knob 7 and the tapered fluted body portion 5. The bead 6 joins the upper base of the frusto-conoidal fluted body 5 at points slightly within the peripheral bounding lines of the flutes, which form the ornamentation of the body portion 5, and thereby a flat shoulder 8, projecting laterally from the lower or base portion of the bead 6, is formed, as shown clearly in Fig. 1 of the drawings.

I claim as my invention—

The design for a bottle-stopper substantially as herein described and illustrated in the accompanying drawings.

In testimony whereof I have signed my name to this specification in the presence of two subscribing witnesses.

HARRY O. BRAWNER.
